SHOW CASE

Leo W. Kennedy, Detroit, Mich.

Application August 11, 1930, Serial No. 474,528

17 Claims. (Cl. 312—114)

This invention relates to show cases and refers more particularly to improvements therein which tend to simplify the construction and render the show cases more efficient.

5 One of the primary objects of this invention is to provide a new and improved means for mounting a show case on a supporting counter or the like.

10 A further object of this invention is to provide means for removably supporting the lights of the show case from the floor thereof.

Still another object of this invention is to provide an improved means for removably supporting the dividers or partitions of the show case in 15 position.

The invention has as a still further object to reduce to a minimum, the number of clips required to hold the lights of the show case in assembled position and contemplates further the provision of a single frame member which constitutes an anchoring means for all of these securing 20 clips.

Other objects and advantages of the invention will be more apparent as the following description proceeds, particularly when reference is had to the accompanying drawings wherein:

Figure 1 is a fragmentary perspective view of a show case constructed in accordance with the teachings of this invention;

30 Figure 2 is a sectional view taken substantially on the line 2—2 of Figure 1;

Figure 3 is a sectional view taken substantially on the line 3—3 of Figure 1;

Figure 4 is an enlarged fragmentary sectional view showing the means provided for removably mounting the lights of the show case in position;

Figure 5 is a fragmentary perspective view showing the parts of the show case in spaced relation to each other;

40 Figure 6 is a sectional view taken substantially on the line 6—6 of Figure 1;

Figure 7 is a fragmentary sectional view taken substantially on the line 7—7 of Figure 6;

Figure 8 is a fragmentary elevational view of a 45 portion of the structure shown in Figure 6;

Figure 9 is a fragmentary sectional view taken substantially on the line 9—9 of Figure 8;

Figure 10 is a detail perspective view of a portion of the structure shown in Figure 8; and

50 Figure 11 is a view similar to Figure 2 showing a slightly modified form of construction.

Referring then particularly to the drawings wherein like reference characters designate corresponding parts throughout all views, there is illustrated in Figure 1 a show case designated gener-

ally by the reference character 10, this show case being provided with the floor 11, end lights 12, front light 13, and top light 14. The floor 11 is bordered by molding strips 15 which are spaced slightly above the upper face of the floor by spacing strips 16, the molding strips being so arranged that they project slightly beyond the edges of the floor. A covering 17 of Monel metal or the like is preferably arranged over the floor 11 and the inner faces of the molding strips 15 and spacing strips 13, this covering having its edges anchored in the molding strips as clearly illustrated in Figure 2 of the drawings.

For supporting the show case there is provided a supporting counter 18 which may be in the form 70 of a table or like member. This supporting counter is provided in its upper face with a recess 19 shaped to receive the floor 11 of the show case as clearly illustrated in Figure 2 of the drawings. The projecting portions of the molding strips 15 75 project beyond the borders of the recess and rest on the portions of the supporting counter which immediately surround the recess. If desired, felt strips 20 may be positioned between the molding strips and the top surface of the supporting 80 counter as clearly illustrated in Figure 4 of the drawings.

By providing a recess in the top of the supporting counter as above described, it will be apparent that the invention provides for a firm 85 mounting of the show case on the supporting counter. Further, by virtue of the fact that the projecting portions of the molding strips rest on the portions of the supporting counter which surround the recess, the general appearance of 90 the supporting counter and the show case is improved.

The invention further contemplates the provision of an improved means for removably mounting the end and front lights in position. 95 To accomplish this the end and front molding strips are provided in their upper faces with grooves 25, adapted to receive the lower edges of the end and front lights respectively. It will be noted that these grooves are vertically opening grooves so that the end and front lights of the show case are, in the form of construction disclosed, supported at substantially right angles to the floor 11 of the show case.

Heretofore it has been customary in mounting 105 a show case light in a molding strip or the like, to provide a detachable strip which constitutes one side of the groove in which the edge of the light is mounted. This has not proven entirely satisfactory because of the fact that whenever 110

- it was desired to remove the light it was necessary to first remove this strip which was generally secured to the molding strip by a plurality of screws or the like. The present invention contemplates the elimination of this difficulty by providing means for yieldably retaining each light in the groove in which it is seated. Thus, by reference to Figure 4 of the drawings it will be noted that there is mounted in each groove 25 a spring strip 26. Each spring strip is provided with a base portion fixed to the base of the groove and a side portion which is returnbent as at 27 to provide a free edge 28 which yieldably engages the inner side of the groove. Thus, the side portion of the spring strip is constantly urged into engagement with the side of the light adjacent the lower edge thereof so that when the edge of the light is inserted in the groove, this edge of the light is gripped by the spring strip and firmly held in position. Obviously, when it is desired to remove the light it is only necessary to draw the same upwardly out of the groove, the spring strip yielding sufficiently for this purpose.
- To provide means for retaining the top light and the upper edges of the end and front lights in position, there is provided a frame member 30. This frame member extends longitudinally of the show case adjacent the upper rear edge thereof and is supported from the floor of the show case by two or more pillars 31, the number of pillars necessary being dependent upon the length of the show case. Each pillar is provided with a base portion 32 bolted or otherwise secured to the floor of the show case and with a flanged top portion 33 which rests within the frame member 30. As clearly illustrated the frame member 30 is preferably U-shaped in cross section, the flange portion 33 of the pillar being bolted or otherwise secured to the base of the U. The top of the frame member 30 constitutes a support for the rear edge of the light 14 and accordingly there is preferably provided a felt covering 34 for the top surface of this frame member. The top surface of the frame member 30 which, it will be understood, is the base of the U, also provides means for engaging the edge of the top light to prevent lateral movement of the same and to accomplish this the top surface of the frame member is extended slightly beyond the end light 12 and is bent upwardly to provide the flange 35 which engages the edge of the top light 14.
- One of the sides of the frame member 30 terminates at the plane of the inner face of the end light 12 and the other side of the frame member is bent inwardly as designated by the reference character 40 to provide a flange 41 which engages the inner face of the end light 12 adjacent the upper edge of the same. A clip 42 fixed as by the bolt 43 to the projecting end of the top of the frame member engages the outer face of the end light 12 adjacent the upper edge of the same and thus cooperates with the flange 41 to provide a channel in which the upper corner of the end light is firmly held.
- For preventing rearward movement of the top light 14 there is provided a clip 45 having the channel portion 46 which embraces the rear edge of the top light and having the flat extension 47 which is bolted or otherwise fixed to the side of the frame member 30. Thus, the top light is prevented from lateral movement by the flange 35 and from movement rearwardly by the clip 46.

To prevent forward movement of the top light and to hold the upper front edges of the front and end lights in assembled position, there is provided a clip designated generally by the reference character 50. This clip is similar in construction to that disclosed in my pending application Serial No. 444,222 filed April 14, 1930, and includes the spaced channel portions 51 adapted to engage the upper edge of the front light, the horizontally disposed channel portion 52 which is adapted to engage the forward edge of the top light and the laterally extending downwardly opening channel portion 53 which is adapted to engage the upper edge of the end light 12. This clip is anchored to the frame member by a brace rod which includes the sections 54 and 55 adjustably connected at their adjacent ends by a turnbuckle 56, the section 54 being hooked at its other end in a projecting portion 57 of the clip 50 and the section 55 being hooked at its rear end in an eye 58 struck from the inner side of the frame member 30.

In accordance with the usual practice, the interior of the show case is preferably divided into a plurality of compartments by glass dividers or partitions 60. For removably supporting these partitions in position there is provided a pair of channel members 61 which are fixed to the floor of the show case as by screws or the like 62. The lower edge of the glass partition seats in these channel members while the upper edge thereof is engaged by a channel shaped clip 63.

As clearly illustrated in Figures 8 to 10, inclusive, of the drawings, there is fixed to the base of the channel shaped clip 63 a stud bolt 64, this stud bolt being held in position preferably by means of a washer 65 which engages the under face of the base of the clip. This stud bolt is provided with a head 66 and is adapted to engage in a slot 67 formed in an angle plate 68, which angle plate is fastened to the frame member 30 by bolts or the like 69. A thumb nut 70 threadedly engages the stud 64 and is adapted to be screwed up against the bottom of the slotted angle member to firmly clamp the slotted portion of the angle clip against the head 66.

In positioning the partitions within the show case, each partition may be first set into the channel members 61 and may then be raised to a vertical position. The top clip 63 is then engaged with the upper edge of the partition and this clip is then moved rearwardly of the partition to position the stud bolt in the slot 67. The thumb nut is then screwed tightly against the head 66 to firmly hold the clip 63 in engagement with the clip 68. Thus it will be noted that the partition will be firmly supported in position and that this partition may be placed in the show case without the use of tools or the like.

From the above it will be apparent that the invention provides a single frame member arranged adjacent the upper rear edge of the show case and provides means for anchoring the several clips utilized for holding the lights in assembled position, to this frame member. Thus, whenever it is desired to disassemble the show case it is only necessary to remove the clips 42 and 45 after which the top light may be removed and then the front and end lights lifted from the grooves in the molding strips.

It will further be apparent that the invention provides clips for holding the upper edges of the

dividers or partitions in position and also provides means for anchoring these clips to the frame member 30.

In Figure 11 a slightly modified form of construction is shown in which slideable doors are provided for closing the rear of the show case. By reference to this figure it will be noted that the bolt 75 which anchors the clip 45' to the frame member 30' also anchors, to the inner face of the side of the frame member, a flange 76 which is formed on the end of a plate 77. This plate projects rearwardly beyond the edge of the frame member in a substantially horizontal position. Fixed to the under face of the plate 77 adjacent the rear edge of the same, is a spacing strip 78 and fixed to the under face of this facing strip, is a second plate 79 which is similar to the plate 77. A second spacing strip 80 is fixed to the plate 79 and supports a plate 81 in spaced relation to the plate 79. Thus, spaced grooves are provided which extend longitudinally of the show case at the upper rear edge of the same for slidably receiving the flanged ends of doors 82 and 83. The lower edges of these doors are supported in grooves 84 and 85 formed by a plurality of plates which are fixed together in the same manner as are the plates 77, 79 and 81 and which are mounted on the upper face of the rear molding strip 15'. Thus, the doors 82 and 83 are mounted for sliding movement, longitudinally of the show case and these doors are so supported that one may be moved over top of the other as clearly illustrated in Figure 6 of the drawings.

From the above it will be clearly apparent that the invention provides an improved construction for supporting a show case on a supporting counter or the like, and an improved means for removably mounting the lights and dividers of the show case in position. It will be apparent that the number of clips required to hold the lights of the show case in assembled position have been reduced to a minimum and that all of these clips may be anchored to a single frame member which constitutes a support for the rear edge of the top light. It will be noted further that the invention provides clips for holding the upper edges of the dividers in position, together with means for anchoring these clips to the single frame member which constitutes an anchor for the light securing clips and that the invention further provides sliding doors for closing the rear of the show case.

While the invention has been described in considerable detail, it is to be understood that the description is for the purpose of illustration only and that the right is reserved to make such changes in the details of construction and arrangement of parts as will fall within the purview of the attached claims.

What I claim as my invention is:

1. In a show case construction, a floor, a molding strip bordering said floor, a light having its lower edge seated in a vertically opening groove in said molding strip, and a spring strip in said groove, said spring strip having a base portion fixed to the base of said groove and having a return bent side portion disposed between the side of said light adjacent the edge thereof and the adjacent side of said groove.

2. In a show case construction, a floor, a molding strip bordering said floor, a light having its lower edge seated in a groove in said molding strip, and a spring strip in said groove, said spring strip having a side portion return bent to provide

a free edge which engages a side of said groove whereby the side portion of said spring strip is yieldably urged into engagement with the side of said light adjacent the edge thereof.

3. In a show case construction, a floor, a top light, a longitudinally extending frame member providing a seat for the rear edge of said top light, a partition, channel members fixed to the floor of said show case for receiving the lower edge of said partition, a clip engaging the upper edge of said partition, a stud carried by said clip, and means anchoring said stud to said frame member.

4. In a show case construction, a longitudinally extending frame member, said member being of inverted U cross sectional shape and having one of its sides bent laterally to provide a depending flange spaced inwardly from the projecting end of the base of the U, a clip secured to the projecting end of the base of the U and cooperating with the said flange to form a channel, and an end light having its upper rear edge positioned in said channel.

5. In a show case construction, a floor, an end light, a longitudinally extending frame member rigidly supported from the floor, said frame member having a portion engaging the inner face of said end light adjacent the upper edge thereof but spaced from the rear edge thereof and having a second portion projecting beyond the upper edge of said end light, and a clip secured to the projecting portion of said frame member and engaging the outer face of said end light adjacent the upper edge of the same.

6. In a show case construction, a longitudinally extending frame member, a top light supported adjacent its rear edge by said frame member, doors slideable longitudinally of said show case for closing the rear thereof, runways for said doors, a clip engageable with the rear edge of said top light, and a single securing means for securing said clip and said runways to said frame member.

7. In a show case construction, a floor, a top light, an end light, a frame member rigidly supported from the floor and constituting a support for the rear edge of said top light, said frame member being provided with a flange at one end engageable with the edge of said top light and being provided with a second flange spaced inwardly from its end and engageable with the inner face of said end light adjacent the upper edge thereof but spaced from the rear edge thereof, and a clip secured to said frame member and engaging the outer face of said end light adjacent the upper edge thereof.

8. In a show case construction, a floor, a top light, an end light, and a frame member rigidly supported from the floor, said member having a substantially horizontal portion constituting a support for the rear edge of said top light and having an integral upwardly turned flange engageable with an edge of said top light and an integral downwardly extending flange engageable with one side of said end light adjacent the upper edge thereof but spaced from the rear edge thereof.

9. In a show case construction, a partition, a frame member, a clip engageable with the upper edge of said partition, a slotted plate rigidly secured to said frame member above said partition, a stud carried by said clip, and means for rigidly securing said stud to said slotted plate.

10. In a show case construction, a frame member, a slotted angle plate fixed to said frame member, a partition, a clip engageable with the

- upper edge of said partition, a stud fixed to said clip and arranged to engage in the slot in said angle plate, and a nut threaded on said stud and engageable with said angle plate for clamping said angle plate to said stud.
11. In a show case construction, means providing a light receiving groove, a light having an edge seated in said groove, and a spring strip extending longitudinally of said groove and having one of its longitudinal edge portions return bent and disposed between a side of said groove and the adjacent side of said light to yieldably retain the edge of said light in said groove.
12. In a show case construction, means providing a light-receiving groove, a light having an edge seated in said groove, and a spring strip extending longitudinally of said groove and having a portion disposed between the edge of said light and the base of said groove and having a second return bent portion disposed between a side of said groove and the adjacent side of the light.
13. In a show case construction, a floor, a frame member extending longitudinally of the case and rigidly supported from the floor, a partition, a clip engaging the upper edge of said partition intermediate the ends thereof, and means anchoring said clip to said frame member.
14. In a show case construction, a floor, a frame member rigidly supported from the floor, a par-
- tion, a clip engaging the upper edge of said partition, and means for detachably securing the clip to the frame member while the clip is in engagement with the said partition.
15. In a show case construction, a frame member, a partition, a clip engaging the upper edge of said partition, a slotted plate carried by said frame member, and a headed element carried by said clip and engageable in the slot in said slotted plate for securing the clip to the frame member. 80
16. In a show case construction, a floor, an end light, and a frame member rigidly supported from the floor and having portions engaging the inner and outer faces of said end light adjacent the upper edge thereof and intermediate the ends thereof for holding said light in position. 90
17. In a show case construction, a floor, an end light, a longitudinally extending frame member rigidly supported from the floor and having a portion engaging the inner face of said end light adjacent the upper edge thereof and intermediate the ends thereof, said frame member having a portion projecting over the top of said end light and beyond the outer face thereof, and means secured to the projecting portion of said frame member and engaging the outer face of said end light adjacent the upper edge thereof. 95
